US00D734980S

(12) **United States Design Patent**
Lipinski et al.

(10) **Patent No.:** US D734,980 S
(45) **Date of Patent:** ** Jul. 28, 2015

(54) **LID FOR A CONTAINER**

- (71) Applicant: **Kraft Foods Group Brands LLC**, Northfield, IL (US)
- (72) Inventors: **Jeffrey M. Lipinski**, Waunakee, WI (US); **Dan R. Feldmeier**, Waunakee, WI (US); **Paul F. Diehl**, Brooklyn, NY (US); **Matthew W. Cowling**, Elmhurst, IL (US); **Philip A. Driskill**, Newburgh, IN (US); **Jordan R. French**, Evansville, IN (US); **Scott L. Fisher**, Evansville, IN (US)
- (73) Assignee: **Kraft Foods Group Brands LLC**, Northfield, IL (US)
- (**) Term: **14 Years**
- (21) Appl. No.: **29/498,676**
- (22) Filed: **Aug. 6, 2014**

(57) **CLAIM**

We claim the ornamental design for a lid for a container, as shown and described.

DESCRIPTION

FIG. 1 is a top perspective view of an embodiment of the claimed design;

FIG. 2 is a front view of the embodiment of FIG. 1;

FIG. 3 is a rear view of the embodiment of FIG. 1;

FIG. 4 is a right side view of the embodiment of FIG. 1;

FIG. 5 is a left side view of the embodiment of FIG. 1;

FIG. 6 is a top view of the embodiment of FIG. 1;

FIG. 7 is a bottom view of the embodiment of FIG. 1;

FIG. 8 is a top perspective view of another embodiment of the claimed design;

FIG. 9 is a front view of the embodiment of FIG. 8;

FIG. 10 is a rear view of the embodiment of FIG. 8;

FIG. 11 is a right side view of the embodiment of FIG. 8;

FIG. 12 is a left side view of the embodiment of FIG. 8;

FIG. 13 is a top view of the embodiment of FIG. 8; and,

FIG. 14 is a bottom view of the embodiment of FIG. 8.
